PISTON RING COMPRESSOR

Wilfred J. Huigens and Glenn Larkin Keeran, Clarinda, Iowa, and Gerald N. McAuliffe, Lincoln, Nebr., assignors to Lisle Corporation, Clarinda, Iowa, a corporation of Iowa

Filed Mar. 5, 1962, Ser. No. 177,673
2 Claims. (Cl. 29—222)

This invention relates to a piston ring compressor to facilitate the compression of piston rings in the grooves of a piston preparatory to inserting the piston in a cylinder.

One object of the invention is to provide a piston ring compressor of the general type having a compression band surrounded by a tension band, and winding means for the tension band, our compressor being further provided with a means to prevent reverse rotation of the winding means in infinitely small steps as distinguished from ratchet and pawl devices for this purpose.

Another object is to provide a holding coil spring tightly wound around a winding drum and having one end anchored so that rotation of the winding drum in the winding direction tends to enlarge the diameter of the coil spring. Accordingly the coil spring automatically reduces in diameter and grips the winding spool to prevent reverse rotation thereof as soon as the handle for operating the winding drum is released.

Still another object is to provide the holding coil spring with manually operable means for increasing its diameter so as to release the winding drum and permit it to rotate reversely when desired.

A further object is to provide another spring wound around the winding drum and frictionally but lightly engaging it so as to act as snubbing means to prevent free reverse rotation of the winding drum which, in the absence of the snubbing spring, would rapidly rotate because of the tendency of the compression band to expand in diameter when permitted to do so.

Further objects and advantages of this invention will become apparent as the following description proceeds and the features of novelty which characterize this invention will be pointed out with particularity in the claims annexed to and forming part of this specification.

A preferred embodiment of the invention is shown in the accompanying drawings, in which:

FIG. 1 is a side elevation of a piston ring compressor embodying our invention;

FIG. 2 is a bottom plan view thereof showing it applied to a piston;

FIGS. 3, 4 and 5 are sectional views on the lines 3—3, 4—4 and 5—5 respectively of FIG. 1; and

FIG. 6 is an exploded perspective view of a winding drum, a holding spring, and a snubbing spring of our device.

On the accompanying drawing we have used the reference numerals 10 to indicate a compression band of spring steel or the like and 12 a tension band surrounding the compression band. One or more of the bands 12 may be provided, two being shown on the drawing. The bands 12 are of thin flexible steel capable of being wound on a drum 28. The drum 28 is tubular as shown in FIG. 3 so that rivets 15 may be inserted therein, then countersink-riveted as indicated at 17 to one end of each band 12. The other end of each band 12 is riveted, each by a rivet 24, to a bearing bracket 22 stamped from sheet metal and provided with four tubular bearings 26 to rotatably support the winding drum 28.

One end of the compression band 10 is also riveted at 24 to the bracket 22 and the band extends about one and one-half times around a piston 16 as shown in FIG. 2, the connecting rod of which is shown at 18. The piston

2

16 has one or more rings 20 therein to be compressed by the band 10, and an overlapping arrangement of this band permits it to be adjusted to pistons of greater and less diameter than shown in FIG. 2 so that the device is readily adjustable to various sizes of pistons in an obvious manner.

A handle 30 is provided for rotating the winding drum 28 counterclockwise in FIG. 3 as indicated by the arrow *a*, thus winding the tension bands 12 thereon for decreasing the diameter of the compression band 10 and thereby compressing the rings 20 into the grooves of the piston 16 to facilitate entry of the piston and rings into a cylinder.

To prevent reverse rotation of the drum 28 without the necessity of having to hold the handle 30, a holding spring 32 is provided consisting of several coils wound tightly around the drum 28 for frictionally engaging the same and holding it against reverse rotation. The cross section of the wire used for this purpose is preferably square so as to provide considerable surface area between the inside diameter of the holding spring and the outside diameter of the winding drum, and the spring is wound so that its inside diameter is several thousandths of an inch smaller than the drum. One end arm of the coil spring 32 indicated at 34 is anchored to the bracket 22 by insertion in a bead 36 formed on the outer traverse thereof, and a rivet 25 is used to prevent spreading of the rib with respect to the inner traverse of the bracket 22. The terminal end of the arm 34 is bent at right angles as indicated at 38 to provide better anchorage. That end of the coil spring 32 is anchored which causes the drum 28, in rotating in its winding direction *a* in FIG. 5, to tend to unwind the spring and thereby increase its diameter so that the winding drum 28 may be readily rotated in the winding direction. However, when rotation stops by release of the handle 30, the drum will rotate reversely only a very small fraction of a degree under the winding up tendency of the holding spring 32, and the spring will thereupon grip the drum and hold it against reverse rotation. Adjustment can thus be secured in infinitely small steps as distinguished from a ratchet-type device in which the steps are of necessity several degrees in extent.

The other end arm 40 of the holding spring has a handle 42 thereon which may be engaged and pushed in the direction of arrow *b* in FIG. 5 for expanding the diameter of the coil 32 and thereby releasing the winding drum to permit its reverse rotation when it is desirable to remove the piston ring compressor from the piston. Thus the holding spring 32 is readily operable in a release direction when desired.

The compression band 10 is initially a straight strip of spring steel and accordingly has considerable tendency to expand in diameter when the winding drum 28 is released. It would therefore be necessary to hold the handle 30 against rampant rotation in the reverse direction and possible damage to the piston ring compressor, but this is an awkward operation.

Accordingly, we have provided a snubber spring 44 shown in FIG. 4 which is similar to the spring 32 but has less than one coil, and is wound only lightly on the drum 28 as for instance being only about .001" smaller in diameter than the winding drum. This spring has its end 46 in a second bead 48 of the bracket 22. The direction of winding is the same as the spring 32 and accordingly the diameter tends to expand on winding rotation in the direction of arrow *a* and to decrease when the direction is reversed. Since this spring is only lightly engaged frictionally with the drum 28, however, it holds the drum against free rotation but permits manual reverse rotation by operation of the handle 30 so as to gently unwind the coils of the band 12 from about the winding drum 28 instead of permitting violent unwinding as would be the case if the snubber spring 44 were omitted.

While less than one coil for the spring 32 is illustrated and described, it may be a multiple coil spring and made of lighter spring wire than the spring 32 yet accomplish the desired result of only a fraction of the frictional drag on the drum 28 as compared with the spring 32.

While there has been shown and described a particular embodiment of this invention, it will be obvious to those skilled in the art that various changes and modifications may be made therein without departing from the invention and, therefore, it is intended in the appended claims to cover all such changes and modifications as fall within the true spirit and scope of the invention.

What we claim as new, and desire to secure by Letters Patent of the United States, is:

1. In a piston ring compressor, a compression band adapted for assuming the shape of the piston which carries the rings to be compressed, said compression band being in the form of a split ring having overlapping ends to permit relative movement between said ends, a tension band of flexible material encircling said compression band for holding it in position and determining the diameter of said compression band, means connected to said tension band for varying the effective diameter thereof, said means comprising a winding drum rotatably carried by one end of said tension band and having one end of said tension band wound thereon, and means to prevent reverse rotation of said drum comprising a holding coil spring wound therearound and frictionally engaging the outer surface thereof, one end of said holding coil spring being fixed relative to said tension band and the other end thereof being free, the direction of winding of said spring being such that there is a tendency to unwind it as said drum is rotated for decreasing the diameter of said ten-

sion band, and said free end terminating in a lever portion projecting beyond the diameter of the coil which is manually engageable for increasing the diameter of said holding coil spring when said lever portion is moved in the direction of winding to thereby permit reverse rotation of said drum.

2. In a piston ring compressor, a compression band adapted for assuming the shape of the piston which carries the rings to be compressed, said compression band being in the form of a split ring having overlapping ends to permit relative movement between said ends, a tension band of flexible material encircling said compression band for holding it in position and determining the diameter of said compression band, means connected to said tension band for varying the effective diameter thereof, said means comprising a winding drum rotatably carried by one end of said compression band and having one end of said tension band wound thereon, and means to prevent reverse rotation of said drum comprising a releasable holding coil spring wound therearound and frictionally engaging the outer surface thereof and a snubbing coil spring having one end connected to said compression band, its other end free and its coil lightly and frictionally engaging around the periphery of said winding drum for snubbing the same against rapid reverse rotation when said holding coil spring is released.
